UNITED STATES PATENT OFFICE.

SOLOMON WILE, OF ROCHESTER, NEW YORK.

SLICING MACHINE.

Application filed January 15, 1923. Serial No. 612,615.

To all whom it may concern:

Be it known that I, SOLOMON WILE, a citizen of the United States, and resident of Rochester, in the county of Monroe and 5 State of New York, have invented certain new and useful Improvements in Slicing Machines, of which the following is a specification.

The present invention relates to slicing 10 machines and more particularly to the type in which a main frame is provided having a cutting mechanism thereon and a carriage movable past the cutting mechanism and having mounted thereon a material supporting 15 carriage movable on the first named carriage toward the cutting mechanism under the action of a toothed member and an advancing pawl. An object of this invention is to provide a novel means for 20 controlling the cooperation of an advance preventing detent with the toothed member, so that the material supporting carriage cannot be accidentally moved independently 25 of the advancing pawl under the action of such cutting mechanism.

To these and other ends, the invention consists of certain parts and combinations of parts, all of which will be hereinafter described: the novel features being pointed 30 out in the appended claims.

In the drawings:

Fig. 1 is a plan view of a slicing machine embodying the present invention;

Fig. 2 shows the slicing machine in elevation;

Fig. 3 is a fragmentary plan view showing the means for feeding the material supporting carriage on the other;

Fig. 4 is an enlarged section on the line 40 4-4, Fig. 3;

Fig. 5 is a section on the line 5-5, Fig. 6;

Fig. 6 is a detail view of the under side of the feeding mechanism for moving the material supporting carriage toward and 45 from the cutting mechanism, the view showing the position of the mechanism occupied when the carriage is held against movement by the advance preventing detent; and

Fig. 7 is a similar view showing the same 50 mechanism in a position it occupies during the movement of the material supporting carriage.

Referring more particularly to the drawings, wherein one embodiment of my invention is shown, 1 indicates the main frame 55 which is provided with tracks or guides 2

on which the carriage 3 is moved, this carriage in turn having thereon tracks or guides 4 for transversely movable material supporting carriage on which any suitable meat clamping means may be arranged. The carriage 3 is moved on a trackway 2 by a hand-wheel 7, in any suitable manner such, for instance, as by the means illustrated in my application filed June 24, 1922, 60 Serial No. 570,643. This hand wheel also turns the cutting mechanism which, in this instance, is a rotary or disc cutter 8 which slices material held on the carriage 5 by the clamping means 6, during the movement 65 of the carriage 3 past the effective cutting edge of the rotary cutter 8. None of the foregoing parts are claimed herein and will not be described in detail. Further information as to the construction and operation of these 70 parts may be obtained from my application aforesaid, if necessary.

This invention has particular reference to the means for controlling the movement of the transversely movable or material supporting carriage 5 on the longitudinally movable carriage 3. In this instance, this means embodies a rack 9 secured to the under side of the material supporting carriage 5 and engaged by a gear 10 which is 75 mounted upon the longitudinally movable carriage 3. This gear 10 in turn meshes with a pinion 11 journalled upon a bearing pin 12 projecting upwardly from a strap 13 secured to the under side of the carriage 3, said pin extending through an opening 14 in the carriage 3 to cooperate with the 80 pinion or gear 10.

The movement of the pinion 11 is preferably effected through a toothed member 95 or wheel 15 which is rigidly secured to the pinion 11 and is adapted to be engaged by an advancing pawl 16 pivoted at 17 to a movable or swinging member 18 and moved toward the ratchet wheel 15 by a spring 100 16^a, the swinging member turning, in this instance, about an axis coincident with the axis of turning of said pinion. A spring 19 of helical formation, secured at 20 to the under side of the carriage 3 and at 21 to the swinging member 18, opposes the movement of the swinging member in one direction while acting on said swinging member to move the latter in the other direction, that is, in the direction to carry 110 the advancing pawl 16 over the teeth of the ratchet wheel 15. The movement of the

swinging member 18 in the opposite direction, that is in the direction to place the spring 19 under tension, is effected preferably through a stop 22 secured on the main frame 5 1 in such a position that the swinging member 18 is moved as the carriage 3 approaches that end of its movement where the cutting action begins to take place. A retaining pawl 23 pivoted to the strap 13 cooperates 10 with the ratchet wheel or member 15 to retain the latter in the position to which it is adjusted, said retaining pawl being acted upon by a spring 24 to hold such pawl against the tooth wheel.

15 One of the important features of this invention is the construction and control of an advance preventing detent for preventing the advance movement of the toothed member 15 under the action of the rotary cutter 20 while the latter is slicing material on the material supporting carriage 5, the knife having a drawing action on the material which, if no means were provided to prevent it, would pull the carriage 5 toward the 25 knife and in this way destroy the accuracy of the feeding action. This advance preventing detent is indicated at 25 being pivoted at 26 to the under side of the carriage 3 and having its nose 27 held toward the 30 ratchet wheel 16 by a spring 28, this nose engaging the ratchet wheel 16 in the direction opposite to the retaining pawl 23 and preventing the advance movement of the toothed member 15. Of course, this 35 advance preventing detent must be moved out of cooperation with the toothed member 15 when the advancing pawl is cooperating with said toothed member to advance the latter. In order that this movement of the 40 advance preventing detent out of engagement with the toothed member 15 may be effected, the swinging member 18 has a cam portion formed by a recess 29 and a curved portion 30, the latter being concentric with the axis of turning of the swinging member 45 18. On the advance preventing detent, a projecting portion 31 is provided beyond the nose 27 and at one side of the latter and this projecting portion 31 cooperates with the 50 swinging member 18, entering the notch 29 so as to engage the toothed member 15, and cooperating with the concentric portion 30 so as to hold the nose 27 out of engagement with the toothed member 15. When the 55 advancing pawl 16 is in the position illustrated in Fig. 6, the projection 31 lies in the notch 29 and engages the toothed member 15, and, as the advancing pawl 16 is swung under the action of the projection 22, the 60 projection 31 rides on the concentric portion 30 bringing the nose 27 out of engagement with the toothed member 15, as shown in Fig. 7, so that said tooth member may be moved under the action of the advancing pawl 16.

With the end in view of determining the amount the carriage 5 is to be moved so as to obtain a slice of the desired thickness, there is provided a controlling member 32 which, in this instance, is mounted to turn 70 on the hub of the gear of the pinion 11 above said toothed member 15. The periphery 32^a of the controlling member 32 is concentric with the axis of turning of the toothed member, but projects beyond the teeth of said member so as to cooperate with the nose of the advancing pawl 16 in order to hold said advancing pawl out of engagement with said toothed member 15. The periphery 32 is not co-extensive with the toothed member, and only covers the segment of said toothed member, so that it is possible by adjusting this controlling member 32 to determine the time of engagement between the advancing pawl 16 and the toothed member 15. The periphery 32^a is not 75 co-extensive with the toothed member, and only covers the segment of said toothed member, so that it is possible by adjusting this controlling member 32 to determine the time of engagement between the advancing pawl 16 and the toothed member 15. When the advancing pawl lies in the position shown in Fig. 6, it engages the periphery 32^a of the controlling member and is held 80 out of engagement with the toothed member 15. At this time the nose 27 of the advance preventing detent 25 engages the toothed member to hold the latter against movement. After the advancing pawl is carried about the axis of the toothed member by the swinging member 18, the latter through the concentric portion 30 shifts the advance preventing detent out of engagement with the toothed member 15, and thereafter the advancing pawl 16 cooperates with the toothed member, due to the fact that it passes off the end 32^b of the concentric portion 32^a of the controlling member, so that the toothed member can be shifted by the advancing pawl 16 during the rest of the movement of 85 said pawl under the action of the projection 22. It is apparent, that, by shifting the position of the end 32^b of the concentric portion 32^a of the controlling member, the amount of advance of the toothed member 15 under the advancing pawl 16 may be varied. Any 90 suitable means may be provided for effecting the adjustment of the controlling member 32. In this instance, a link 33 is pivotally connected at 34 to the controller 32 and is pivotally connected at 35 to an arm 36 on 95 a shaft 37 journalled on the carriage 3 and controlled through a thumb wheel 38. By turning this thumb wheel 38 the controlling member 32 is adjusted. The mounting of this controlling member is the same as a 100 similar member in my application aforesaid and will not be described in detail herein.

With the end in view of permitting the carriage 5 to be moved away from the cutter, a controlling lever 39 is employed pivoted at 40 to the carriage 3 and having an end 41 formed to cooperate with projections 42, 43, and 44 provided respectively on the advancing pawl 16, the advance preventing detent 25 and the retaining pawl 23. Owing 105

ing to the curved formation of this portion 41, it is adapted to cooperate with the projection 42, notwithstanding the position of the latter about the axis of the toothed 5 wheel with reference to the other pawls or detents.

From the foregoing it will be seen that there has been provided a slicing machine in which there is employed an advance preventing means for preventing the advance movement of the material supporting carriage under the action of the cutting mechanism, this advance preventing means cooperating with a toothed member and being 10 controlled by a movable member on which the advancing pawl is mounted and the advancing pawl being in turn controlled by a member which determines the amount said pawl will effect the movement of the 15 toothed member, the advancing pawl being held out of engagement with the toothed member by its controlling member during the time that the advance preventing pawl or detent is in engagement with said toothed 20 member.

What I claim as my invention and desire to secure by Letters Patent is:

1. In a slicing machine the combination with a main frame, cutting mechanism 30 mounted on the main frame, a carriage movable past the cutting mechanism, and a material supporting carriage movable on the first mentioned carriage transversely of the latter toward and from the cutting 35 mechanism, of mechanism for feeding the material supporting carriage on the first mentioned carriage embodying a toothed member mounted on the first mentioned carriage and geared to the second mentioned 40 carriage, a movable member carrying an advancing pawl mounted on the first mentioned carriage and cooperating with said toothed member, means on the main frame for cooperating with the movable member 45 to effect the movement of the toothed member, an advance preventing means cooperating with the toothed member to prevent the advance movement thereof under the action of the cutting mechanism operating upon 50 the material supporting carriage, and means connected with said movable member for effecting the movement of said advance preventing means out of engagement with the toothed member when said movable member is moved to cause the advancing pawl to shift the toothed member.

2. In a slicing machine, the combination with a main frame, cutting mechanism mounted on the main frame, a carriage movable past the cutting mechanism, and a material supporting carriage movable on the first mentioned carriage transversely of the latter toward and from the cutting mechanism, of mechanism for feeding the second 65 mentioned carriage on the first mentioned

carriage embodying a ratchet wheel on the first mentioned carriage geared to the second mentioned carriage, a swinging member mounted to turn about the axis of the ratchet wheel on the first mentioned carriage, an advancing pawl carried by said swinging member and cooperating with the ratchet wheel, means on the main frame for cooperating with the swinging member to effect the movement of the latter and through such movement to effect the movement of the ratchet wheel, an advance preventing detent cooperating with the ratchet wheel to prevent the advance movement thereof, and means on the swinging member for moving said advance preventing detent out of cooperation with the ratchet wheel after the swinging member is moved under the action of the means on the base frame. 70 75 80 85

3. In a slicing machine, the combination with a main frame, cutting mechanism on the main frame, a carriage movable past the cutting mechanism, and a material supporting carriage movable on the first mentioned carriage transversely of the latter toward and from the cutting mechanism, of mechanism for feeding the second mentioned carriage on the first mentioned carriage comprising a ratchet wheel mounted on the first mentioned carriage and geared to the second mentioned carriage, a swinging member mounted to turn about the axis of turning of the ratchet wheel and having a cam surface thereon, an advancing pawl mounted on said swinging member to cooperate with the ratchet wheel, means on the main frame cooperating with the swinging member to effect the movement of the latter and through such movement to effect the movement of the ratchet wheel by means of said advancing pawl, and advance preventing means cooperating with the ratchet wheel to prevent the advance movement thereof and cooperating with the cam so as to be moved into and out of cooperation with the ratchet wheel through the movement of the swinging member. 90 95 100 105 110

4. In a slicing machine, the combination with a main frame, a cutting mechanism mounted on the main frame, a carriage movable past the cutting mechanism, and a material supporting carriage movable on the first mentioned carriage transversely of the latter toward and from the cutting mechanism, of mechanism for feeding the second mentioned carriage on the first mentioned carriage embodying a toothed member on the first mentioned carriage having connection with the second mentioned carriage, a movable member mounted on the first mentioned carriage, an advancing pawl on the movable member cooperating with the toothed member, means on the main frame cooperating with the movable member to effect the movement of the latter and through 115 120 125 130

such movement to effect the movement of the toothed member, a member on the first mentioned carriage adjustable to hold the advancing pawl out of engagement with the toothed member during any desired amount of movement of said pawl by the means on the main frame so that the amount of movement of the toothed member may be varied, an advance preventing means cooperating with said toothed member to prevent advance movement thereof under the action of the cutting mechanism, and means for throwing the advance preventing means out of cooperation with the toothed member before the advancing pawl moves into cooperation with said toothed member and into said cooperation with said toothed member after the advancing pawl moves out of cooperation with the toothed member, said last mentioned means being controlled by the movable member which carries the advancing pawl.

5. In a slicing machine, the combination with a main frame, cutting mechanism mounted on the main frame, a carriage movable past the cutting mechanism, and a material supporting carriage movable on the first mentioned carriage transversely of the latter toward and from the cutting mechanism, of mechanism for feeding the second mentioned carriage on the first mentioned carriage embodying a ratchet wheel mount-

ed on the first mentioned carriage and geared to the second mentioned carriage, a swinging member mounted to turn about the axis of turning of the ratchet wheel on the first mentioned carriage, an advancing pawl arranged on the swinging member and cooperating with the ratchet wheel, means on the base frame for cooperating with the swinging member to effect the movement of the latter and through such movement to effect the movement of the ratchet wheel, a member mounted to turn about the axis of turning of the ratchet wheel and cooperating with said advancing pawl to hold the latter out of engagement with the ratchet wheel during any desired movement of the swinging member, a cam surface on the swinging member, and an advance preventing detent cooperating with the ratchet wheel to prevent the movement thereof under the action of the cutting mechanism, said advance preventing detent having cooperation with the cam surface on the swinging member, so that the advance preventing detent moves out of cooperation with the ratchet wheel when the advancing pawl is moved by the swinging member into cooperation with the ratchet wheel and is moved into cooperation with the ratchet wheel when said advancing pawl is moved out of cooperation with the ratchet wheel.

SOLOMON WILE.
